ROLLING MACHINE

Charles W. Sinclair, Detroit, Mich., assignor to
 Kelsey-Hayes Wheel Company, Detroit, Mich.,
 a corporation of Delaware

Application May 13, 1935, Serial No. 21,288

8 Claims. (Cl. 80—5)

This invention relates generally to rolling machines and refers more particularly to apparatus for rolling strip stock having angularly disposed portions to form an arcuate section.

5 Although the machine forming the subject matter of this invention is capable of many and diversified uses, nevertheless, it finds particular utility when employed for forming T-section strip stock into a brake shoe of arcuate configuration.

10 Heretofore, in rolling T-section strip stock into an arcuate section with the stem or web of the T extending inwardly, considerable difficulty has been encountered in preventing the 15 web from buckling or from otherwise becoming deformed during the upsetting operation, and it is one of the principal objects of this invention to overcome this difficulty by providing 20 means for applying a continuous pressure on opposite sides of the web as the stock is being rolled to the desired contour.

Another object of this invention which contributes materially to overcoming the difficulty previously set forth, consists in providing a 25 machine having means for applying a constant pressure on opposite sides of the web during the rolling operation, irrespective of variations in the thickness of the web.

A further advantageous feature of the present 30 invention resides in the provision of a rolling machine rendering it possible to form a rolled exterior surface on the head of the T having all 35 of the points thereof in radial planes passing through the axis of the shoe lying in straight lines or, in other words, provides for obtaining a rolled exterior face on the head of the T which forms a section of a truly cylindrical surface. This latter feature is desirable in that it insures 40 utilizing the entire area of the exterior surface of the lining applied to the shoe as effective braking area. This feature, as well as the foregoing objects, will be made more apparent as this description proceeds, especially when considered in connection with the accompanying 45 drawings, wherein:

Figure 1 is a semi-diagrammatic sectional view of a rolling machine constructed in accordance with this invention;

Figure 2 is a sectional view taken on the plane 50 indicated by the line 2—2 of Figure 1;

Figure 3 is an enlarged sectional view of a portion of Figure 2;

Figures 4, 5, and 6 are respectively, cross sectional views taken on the lines 4—4, 5—5 and 55 6—6 respectively of Figure 1.

Referring now to the drawings, it will be noted that there is illustrated in Figure 1, a rolling machine 10 comprising a master or supporting roll 11 and a plurality of forming rolls 12 predeterminedly positioned with respect to the 5 master roll to cooperate with the latter in forming a strip of T-section stock 13 into an arcuate brake shoe with the stem or web 14 of the T extending inwardly from the head 15 thereof. Obviously, in rolling the strip of T-section stock 10 13 to an arcuate contour with the web 14 extending inwardly there is a tendency for the web 14 to wrinkle or buckle, and in order to prevent deformation of the web during the rolling operation irrespective of any variation in 15 thickness that may occur in the web, a constant pressure is applied to the web as the strip is rolled or upset by the cooperating forming rolls. In the present instance, hydraulic pressure is applied to the web 14 of the stock during the 20 rolling operation, through the medium of the master forming roll 11, and for accomplishing this result, the roll 11 is formed of two cooperating sections 16 and 17 spaced axially from each other a sufficient distance to receive the 25 web 14 therebetween. As shown in Figures 1 and 2, the section 17 is keyed on a drive shaft 18 and the section 16 is provided with an axially extending hub 19 keyed to a corresponding hub 20 on the section 17. It will also be noted from 30 the above figures, that the end of the hub 19 on the section 16 projects beyond the end of the hub 20 on the section 17 for engagement with a suitable adjusting nut 21 threaded upon the drive shaft 18 and normally locked in adjusted 35 position, by means of a lock nut 22 also threaded on the drive shaft 18. The arrangement is such as to provide for varying the width of the space between the adjacent work engaging faces of the master roll sections to accommodate web 40 portions having different thicknesses.

It will be observed from the foregoing, that the adjusting nuts, as well as the master roll sections, rotate as a unit with the drive shaft 45 18 and, in the present instance, the latter is driven from a suitable source of power (not shown) connected to a drive gear 23 secured to the forward end of the shaft. In this connection, it will be noted that the shaft is journaled upon opposite sides of the forming roll 11 in 50 suitable bearings 24 fixedly secured to the machine frame.

It has previously been stated that the web 14 of the T-section stock is clamped under pressure between the sections of the master forming 55

roll, and this is accomplished by holding the section 17 of the roll under compression against the web 14 by hydraulic means comprising a piston 25 surrounding the drive shaft in abutting relation to the front side of the section 17. In the specific embodiment of the invention selected herein for the purpose of illustration, the piston 25 is composed of two rings 26 and 27 secured together with a suitable seal 28 disposed therebetween. As shown in Figure 2, the piston 25 slides upon the drive shaft 18 and is housed within an annular recess 29 formed in the rear face of a suitable collar 30 disposed between the front side of the section 17 of the master roll and an enlargement 31 of the shaft. In detail, the ring 26 forms the actual effective portion of the piston, in that the same abuts the front face of the section 17 of the forming roll 11 and the inner and outer surfaces respectively, slidably engage the drive shaft 18 and the annular surface of the recess 29. The ring 27 is free from engagement with both of the aforesaid surfaces and merely functions to secure the annular seal 28 to the front side of the ring 26, through the medium of the screws 32. In this connection, it will be observed from Figure 2, that the seal is channel-shaped in cross section having the inner flange in wiping engagement with the drive shaft and having the outer flange in wiping engagement with the annular surface of the recess. It may also be pointed out at this time, that an annular seal 33 is provided between the rear face of the collar 30 and the adjacent side of the section 17 of the master roll. This seal is located radially outwardly beyond the recess 29 in the collar and is of such a material as to effectively maintain a seal irrespective of limited axial displacement of the section 17 of the roll.

During the rolling operation, the piston 25 is urged into engagement with the front side of the section 17 of the master roll by a fluid under pressure admitted into the annular recess 29 in rear of the piston, through the medium of a supply passage 35 extending axially through the drive shaft 18 and communicating with the recess through the medium of outwardly extending passages 36. The passages 36 are arranged in pairs symmetrical with the supply passage 35, and the passages of each pair communicate with each other at the point of communication of the same with the annular recess 29, in the manner clearly shown in Figure 2. The fluid under high pressure is admitted into the supply passage 35 at the forward end of the shaft from a suitable source (not shown), and the rear end of the supply passage 35 is closed by a fitting 37 secured to the rear end of the shaft and having a suitable relief valve 38 associated therewith to permit relieving the pressure on the section 17 of the master roll upon completion of the rolling operation. Thus it will be observed that the supply passage 35 extends for the full length of the drive shaft 18 and that the fluid under pressure in this passage is conducted to the annular recess 29 in advance of the piston 25, by means of the plurality of pairs of passages 36. With this construction, a continuous pressure may be exerted upon the section 17 of the master roll, during the rolling operation, of sufficient force to positively prevent buckling or wrinkling of the web 14 of the stock as the same is formed to an arcuate contour.

Referring again to Figure 2, of the drawings,

it will be noted that both sections of the master roll are provided with peripheral portions 39 having flush exterior surfaces for engaging the inner surface of the head 15 of the T-section stock upon opposite sides of the web 14 thereof. As stated above, the forming rolls 12 cooperate with the peripheral portions 39 of the master roll 11 to bend the strip of T-section stock to an arcuate contour and as shown in Figures 2, 3, 4, 5 and 6, the peripheries of the forming rolls 12 are recessed as at 40, to receive the peripheral portions of the master roll 11 with the head 15 of the stock therebetween. It will also be noted from the above figures, that the first two of the four rolls shown are provided with annular grooves 41 in the work engaging surfaces thereof. These grooves are so positioned in the work engaging surfaces of the rolls as to assume positions directly opposite the web 14 of the T-section stock during the rolling operation and, consequently, operate to roll a raised bead 43 on the exterior surface of the head 15 of the T-section stock directly opposite the web 14. It will be observed upon reviewing Figures 2, 3, and 4, that the annular groove in the second forming roll shown in Figure 4, is slightly smaller than the groove in the first forming roll, illustrated in Figure 3, and that the groove is entirely eliminated from the succeeding rolls. The arrangement is such as to gradually iron out the bead 43 during the rolling operation, and this is desirable since it renders it possible to eliminate the usual depression found to exist in the exterior surface of the rolled stock opposite the stem of the T. The existence of this depression, resulting from prior methods of rolling, caused considerable concern in the trade, since it had the tendency of reducing the effective braking area of the shoe. With the present apparatus, however, a brake shoe may be rolled having an exterior face forming a section of a truly cylindrical surface and, as a consequence, the entire outer surface of the shoe may be employed as effective braking area.

Each of the first three forming rolls 12 is fixed to a suitable shaft, which in turn is journaled in any suitable manner in the frame of the machine and is driven at a predetermined speed from the drive shaft 18, through the medium of suitable gearing. In the present instance, the gearing comprises a gear 47 fixed to the drive shaft 18 and meshing with a gear 48 fixed to the shaft 49 upon which the first forming roll of the series 12 is secured. The aforesaid gearing also includes a gear 50 secured to the hub portion 19 of the forming roll section 16 and meshing with gears 51 and 52 (shown in Figure 1 by the dot and dash lines) and respectively secured to the shafts 53 and 54, upon which the second and third forming rolls of the series 12 are secured. The fourth forming roll of the series 12 is shown in Figure 6 as being formed integral with a shaft journaled in the machine frame by suitable ball bearings supported in a manner (not shown) to permit yieldably urging the shaft toward the master roll 11.

Thus from the foregoing, it will be observed that I have provided a relatively simple rolling machine for forming brake shoes of T-section stock, embodying effective means for preventing the web of the stock from buckling or wrinkling during the rolling operation. It will also be apparent that I have provided a rolling machine having means rendering it possible to provide

a brake shoe having a rolled exterior face forming a section of a truly cylindrical surface.

What I claim as my invention is:

1. In a machine for forming a metal section with a rolled surface having all of the points thereof in transverse planes lying in straight lines, a member engageable with the opposite surface of the stock to support the same, a forming roll predeterminedly arranged with respect to said member for engagement with the rolled surface aforesaid of the stock and having an annular groove in the periphery thereof for forming a bead on said latter surface, and additional rolls for gradually ironing out the bead.

15 2. In a machine for forming a metal section with a rolled surface having all of the points thereof in transverse planes lying in straight lines, a member engageable with the opposite surface of the stock to support the same, and a plurality of forming rolls predeterminedly located with respect to the member to successively engage the first named surface of the stock, one of the rolls having an annular recess in the periphery thereof to form a bead on the first 25 mentioned surface of the stock and another of the succeeding rolls having an annular recess of less depth than the recess aforesaid to reduce the size of the bead.

3. In a machine for forming a metal section with a rolled surface having all of the points thereof in transverse planes lying in straight lines, a member engageable with the opposite surface of the stock to support the same, a plurality of forming rolls predeterminedly located 35 with respect to the member to successively engage the first named surface of the stock, one of the rolls having an annular recess in the periphery thereof to form a bead on the first mentioned surface of the stock and another of the succeeding rolls having an annular recess of less depth than the recess aforesaid to reduce the size of the bead, and means for subsequently completely ironing out the bead.

4. In a machine for forming from T-section strip stock an arcuate member provided with a rolled exterior surface on the head of the T having all of the points thereof in radial planes passing through the center of the arcuate section lying in straight lines, a master roll having sections disposed upon opposite sides of the stem of the T and having peripheral portions engaging the undersides of the head of the T, and a plurality of forming rolls predeterminedly positioned with respect to the master roll to successively engage the exterior surface of the head of the T, one of the forming rolls having an annular recess in the periphery thereof to form a bead on said exterior surface and another of the forming rolls having an annular recess in the periphery thereof

of less depth than the annular recess aforesaid to reduce the size of the bead.

5. In a machine for forming from T-section strip stock an arcuate member provided with a rolled exterior surface on the head of the T having all of the points thereof in radial planes passing through the center of the arcuate section lying in straight lines, a master roll having sections disposed upon opposite sides of the stem of the T and having peripheral portions engaging the undersides of the head of the T, a plurality of forming rolls predeterminedly positioned with respect to the master roll to successively engage the exterior surface of the head of the T, one of the forming rolls having an annular recess in the periphery thereof to form a bead on said exterior surface and another of the forming rolls having an annular recess in the periphery thereof of less depth than the annular recess aforesaid to reduce the size of the bead, means for subsequently ironing out the bead, and means for relatively moving the master roll sections toward each other to clamp the stem of the stock during the rolling operation.

10 6. In a rolling machine, a master roll, a plurality of rolls spaced from each other circumferentially of the master roll and located beyond the periphery of said master roll to cooperate with the latter in forming a path of travel for a strip of stock, the roll at the entrant end of the 15 path of travel having an annular groove in the periphery thereof to form a bead on the stock and the succeeding rolls cooperating with the master roll to gradually iron out the bead.

20 7. In a rolling machine, a forming roll having 25 the peripheral surface engageable with one surface of a strip of stock and having an annular groove in the periphery thereof between opposite ends of the same for forming a bead on the strip of stock between the opposite side edges thereof, 30 and means positioned beyond said roll and engageable with the surface aforesaid of the stock to iron out said bead and provide a flush surface on the stock having all of the points thereof in 35 transverse planes lying in straight lines.

8. In a rolling machine, a plurality of rolls 40 spaced from each other along the path of travel of a strip of stock to be rolled and having peripheral portions engageable with one surface of the stock, the roll at the entrant end of the machine 45 having an annular groove in the periphery thereof between opposite ends of the same to form a bead on the surface aforesaid of the stock between the side edges of the latter, means positioned beyond said roll in the direction of travel 50 of the stock for gradually reducing the size of said bead, and means beyond the last named means for ironing out the bead to form a flush 55 rolled surface on the stock.

CHARLES W. SINCLAIR.
